ASSIGNOR TO WALTER D. LEMON, OF NEWARK, NEW JERSEY

HOLDER FOR BAGS

Application filed November 20, 1928. Serial No. 320,606.

Our invention relates to improvements in a holder for paper bags, wrapping paper and the like, for use in stores, and market stalls.

The object of this invention is to provide a holder for bags and the like adapted for holding the bags in a novel manner, which will insure the bags being held in an accessible position suitable for removing the bags from the holder one at a time; a further object is to provide a holder for holding the bags from tilting, or swinging, by the wind, when used in an open market stall; a still further object is to provide a holder having jaws carrying pins adapted for perforating the entire bundle of bags, which may be inserted in the holder, so that every bag will be held by the pins; a still further object is to provide a novel locking device for holding the movable jaw in the open position, against the action of a heavy spring; a still further object is to provide means for releasing the locking device, whereby the tension of the spring will force the pins through the bags during the closing of the jaws; a still further object is to provide means for protecting the points of the pins from striking the metal parts of the holder when the jaws are closed; a still further object is to provide hardened reinforcing plates for preventing the parts subjected to the force of the spring from wearing, thus permitting the other parts of the holder to be formed of cheaper material and the entire holder manufactured at a low cost; and a still further object is to provide a base plate having several holders arranged thereon, positioned in a horizontal row whereby bags of different sizes may be held side by side; these together with various other novel features of construction and arrangement of the parts constitute our invention, which will be hereinafter more fully described and claimed.

In the accompanying drawings Fig. 1 represents a side elevation of our improved holder; Fig. 2 is a front elevation of Fig. 1; Fig. 3 is a view similar to Fig. 1 showing the movable jaw locked in the open position; Fig. 4 is an end view, partly in section of Fig. 2, looking from below; Fig. 5 is a side elevation of the movable jaw, detached; Fig. 6 is a vertical sectional view, as on line 6—6 of Fig. 2,

showing the movable jaw in the open position; Fig. 7 is an end view of Fig. 2 looking from above; and Fig. 8 is a front elevation, drawn on a smaller scale, showing a plurality of holders arranged upon a base in a novel manner, adapted for holding the bags side by side.

In the accompanying drawings in which like reference characters refer to like parts 1 represents a base adapted for mounting the holder upon a wall in any suitable manner. Upon the base 1 is secured the fixed jaw 2 of the holder which comprises a single unit having a base plate 3, rigidly secured to said base 1 and bearing members 4 and 5 projecting at right angles from the base plate 3 and in which the shaft 8 is mounted. The base plate 3, at its lower end, is provided with a rib 10 which is bent at right angles to the base plate 3 and projects outwardly therefrom, and the outer edge of the rib 10 is provided with teeth 12 against which the bundle of paper bags will rest when secured in the holder.

Upon the fixed jaw 2 of the holder is a conical pin 14 having a shoulder head 15 which extends through both the base 1 and the base plate 3 and forms a means for holding the base plate and the base together, with the point of the pin projecting toward the opposite jaw and adapted to be inserted into the bundle of bags.

Mounted upon said shaft 8 is a movable jaw 20, consisting of a front plate 21 having cheek plates 22 and 23 projecting at right angles to the front plate and adapted to be inserted between the bearing members 4 and 5 of the fixed jaw, whereby the movable jaw may be rotated upon the shaft 8 relatively to the fixed jaw. The lower portion of the front plate 21 of the movable jaw is provided with a handle 25 for operating the latter. Said front plate 21 is also provided with two conical pins 27 and 28 which are rigidly secured to said front plate 21, with the points of the pins projecting inwardly toward the jaw 2. Said pins 27 and 28 are arranged in horizontal alignments with the pin 14 on the fixed jaw and are located in spaced relation to the pin 14 whereby each pin will pierce the bundle of bags at different places without tear-

ing the bags, and said pins will force themselves into the bundle in such a manner that every bag will be held by the pins, from which pins the bags may be torn off one at a time by pulling downwardly upon the bags.

5 A heavy spring 30 is coiled about the shaft 8 and is adapted for forcing the jaws together. One end of said spring forms an arm 31 which is held against the base plate 3 and provided with a bent end 32 which is bent so as to extend parallel with the length of the shaft 8, and abuts the inside surface of the bearing member 4. Said end 32 being greater in length than the thickness of the cheek plate 22 of the movable jaw, thus holds the entire spring 30 away from the cheek plate 22 and relieves the latter of any friction due to end thrust of the spring when the movable jaw is in rotation, thus insuring the free movement of the movable jaw. The opposite end of the spring 30 is provided with an elongated loop 35 which presses against the movable jaw and tends to force the latter into the closed position.

20 Said spring terminates with the free end 36 which normally rests in a notch 40 formed in the cheek plate 23, and when the movable jaw is in the closed position said free end 36 of the spring also rests in a notch 48 formed in the bearing member 5, as shown in Fig. 1. The bearing member 5 is provided with a cam surface 50 over which the free end 36 of the spring rides when the movable jaw is being opened. When the movable jaw is fully open, the free end 36 of the spring drops into a notch 52 formed in the bearing member 5 and when the free end of the spring occupies the notch 52 the shoulder 54 will hold the spring against its tendency to close the movable jaw, and the notch 40 in the cheek plate 23 occupied by the end 36 of the spring prevents the movable jaw from closing.

25 The cheek plate is provided with a cam surface 41 for lifting the free end 36 of the spring out of the notch 52 in the bearing plate 5 when it is desired to close the movable jaw 20. During the initial closing movement of the movable jaw said cam surface 41 of the cheek plate will slide the end 36 of the spring 30 radially during the rotating movement of the cheek plate 23, which movement of the spring is made possible by the elongated loop 35 formed upon the spring which permits the end 36 of the spring to have a radial movement, thus said cam surface 41 will gradually force the free end 36 of the spring outwardly until it is disengaged from the shoulder 54, when the coiled portion 35 of the spring 30 will move the movable jaw into the closed position and the free end 36 of the spring will again occupy the lower portion of the notch 40 and 48 formed in the cheek plate 23 and in the bearing member 5, as shown in Fig. 1.

30 Said spring 30 is of heavy construction so that it will close the movable jaw with suffi-

cient force to drive the pins through a bundle of bags, and as the entire holder is formed of soft metal it is necessary to provide reinforcing parts to prevent the rapid wearing of the parts engaged by the spring. The movable jaw 20 is provided with a hardened steel plate 60 which is secured to the under surface of the movable jaw by a rivet 61, and by a depressed tongue 62 which enters the V-shaped end formed on said reinforcing plate 60, thus rigidly holding the latter from displacement. The opposite end of the reinforcing plate 60 is provided with a bearing portion 64 which is bent upwardly at right angles to the plate 60 and forms a surface upon which the loop 35 of the spring 30 rides when it is moved radially.

35 The bearing member 5 is also provided with a reinforcing hardened steel plate 70, which is secured upon the outside surface of the bearing member 5 by the head of the shaft 8 and is prevented from turning by a tongue 72 formed upon the bearing member 5, which tongue enters a slotted end portion of the reinforcing plate 70. The opposite end of the reinforcing plate is provided with a curved cam surface 74 corresponding to the shape of the cam surface 50 formed upon the bearing member 5 and said plate 70 is also provided with a shoulder and a notch corresponding with the shoulder 54 and the notch 52 formed in the bearing member 5 respectively, thus the reinforcing plate 70 prevents the wearing away of the bearing member 5.

40 The cheek plates 22 and 23 of the movable jaw are provided with feet 80 which rest upon the base plate 3 when the jaws are closed, thus preventing the points of the pins 14, 27 and 28 from being injured by coming in contact with any metal parts.

45 Fig. 8 illustrates a base 82 of sufficient length for carrying two or more holders 83 which are positioned so that the shafts 84 forming the axes of the movable jaws of the holders extend parallel with the length of the base 82, whereby a number of bags 85 of different sizes may be suspended from the holders and arranged side by side, thus greatly facilitating in selecting a bag of the desired size, as the bags do not over-lap each other, this feature is of particular advantage when the holders are used at an open market stall where the wind may blow the bags and tend to disarrange the bundles. By mounting the holders side by side upon a base the bundles are always kept separate and by providing the holders with pins positioned in spaced relation to each other the bags can not swing as they would if carried by a single pin.

50 The operation of our invention is as follows:

55 The base is rigidly secured upon any suitable surface, and the movable jaw may be readily opened by means of the handle into the position shown in Figs. 3 and 6, in which

position it is locked by means of the end 36 of the spring falling back of the shoulder 54, as clearly shown in Fig. 3. Bundles of bags or sheets of wrapping paper are placed with their upper edges between the points of the pins carried by the jaws of the holders, as shown in Fig. 8. The handle of the movable jaw is then pressed downwardly until the cam 50 forces the end 36 of the spring 5 free of the shoulder 54, thus permitting the 10 spring to force the movable jaw into the closed position with the pins projecting into the bags or sheets of wrapping paper from which they may be readily removed one at 15 a time. By arranging several holders upon a single base, different sizes of bags or sheets of paper may be held separately upon the holders.

Various changes may be made in the construction of the parts of the holder without departing from our invention.

We claim:—

1. A holder comprising a base adapted to be mounted in a fixed position, a jaw secured 25 upon said base, a jaw movably mounted upon the fixed jaw, a spring tending to force said jaws together, a rib upon the fixed jaw projecting toward the movable jaw, said rib having a series of teeth formed upon the outer 30 edge thereof, and a pin upon the movable jaw adapted to pierce an article placed between the jaws and force said article toward said rib.

2. A holder comprising a jaw adapted to 35 be held in a fixed position, bearing plates upon said jaw, a shaft mounted in said plates, a movable jaw, cheek plates upon the latter rotatably mounted upon said shaft, a spring tending to force said jaws together, a pin 40 upon one of said jaws adapted to pierce an article placed between the jaws, a foot plate upon one of said plates adapted to strike against the opposite jaw and prevent the point of the pin from striking the jaw.

45 3. A holder comprising a jaw adapted to be held in a fixed position, bearing plates upon said jaw, a shaft mounted upon said plates, a movable jaw, cheek plates upon the latter rotatably mounted upon said shaft, a spring coiled around said shaft having one 50 end engaging the fixed jaw, said spring having a yieldable end portion rotatably and radially movable relatively to said shaft, a shoulder upon the cheek plate of the movable jaw against which the free end of the spring engages tending to close the jaws, a shoulder upon the bearing plate for engaging the end portion of the spring when the jaws are open, and a cam surface formed 55 upon the cheek plate for lifting the end of the spring radially to disengage the latter from said shoulder on the bearing plate upon the initial movement of the movable jaw toward the closed position.

60 4. A holder comprising a jaw adapted to

be held in a fixed position, bearing plates upon said jaw, a shaft mounted upon said plates, a movable jaw, cheek plates upon the latter rotatably mounted upon said shaft, a spring coiled around said shaft having one 65 end engaging the fixed jaw, said spring having a yieldable end portion rotatably and radially movable relatively to said shaft, a shoulder upon the cheek plate of the movable jaw against which the free end of the spring 70 engages tending to close the jaws, said cheek plate having a notch formed therein adjacent to said shoulder in which notch the end portion of said spring normally rests for moving the movable jaw with the spring, a 75 shoulder upon the bearing plate for engaging the end of the spring when the jaws are open, said bearing plate having a notch formed therein adjacent to the shoulder upon the bearing plate, and a cam surface formed 80 upon the cheek plate for lifting the end of the spring radially out of said last mentioned notch, for disengaging the spring from the shoulder on the bearing plate upon the initial movement of the movable jaw toward the 85 closed position.

5. A holder comprising a jaw adapted to be held in a fixed position, bearing plates upon said jaw, a shaft mounted upon said plates, a movable jaw, cheek plates upon the latter rotatably mounted upon said shaft, a spring coiled around said shaft having one 90 end engaging the fixed jaw, said spring having a yieldable end portion rotatably and radially movable relatively to said shaft, a reinforcing plate secured to said movable jaw, said reinforcing plate being of relatively harder material than the movable jaw, said reinforcing plate having a portion interposed between the points of contact of the spring 95 and the movable jaw, and means upon one of said bearing plates for engaging said end portion of the spring when the jaws are in the open position.

6. A holder comprising a jaw adapted to be held in a fixed position, bearing plates upon said jaw, a shaft mounted upon said plates, a movable jaw, cheek plates upon the latter rotatably mounted upon said shaft, a spring coiled around said shaft having one 100 end engaging the fixed jaw, said spring having a yieldable end portion rotatably and radially movable relatively to said shaft, a reinforcing plate secured upon one of said bearing plates, said reinforcing plate being 105 of relatively harder material than the bearing plate, said reinforcing plate having a cam surface thereon over which the end portion of the spring slides, and a shoulder upon said reinforcing plate for engaging the end portion of the spring when the jaws are in the open position.

7. A holder comprising a jaw adapted to be held in a fixed position, bearing plates upon said jaw, a shaft mounted upon said 110

plates, a movable jaw, cheek plates upon the latter positioned between the bearing plates and rotatably mounted upon said shaft, a spring encircling said shaft, said spring having one arm thereof extending radially from said shaft and engaging the fixed jaw, a part upon said arm extending parallel with said shaft with the end thereof abutting the bearing plate at a point beyond said cheek plate whereby the spring will be prevented from making frictional contact with the rotatable cheek plate, said spring having a yieldable end portion formed upon the opposite end thereof for engaging the movable jaw, means upon the bearing plate for engaging said yieldable end portion of the spring for holding the movable jaw in the open position against the tension of the spring.

In testimony whereof we affix our signatures.
